(57) **CLAIM**

We claim the ornamental design for a handheld electronic device, as shown and described.

DESCRIPTION

FIG. 1 is a front elevational view of a handheld electronic device;

FIG. 2 is a back elevational view thereof;

FIG. 3 is a left elevational view thereof;

FIG. 4 is a right elevational view thereof;

FIG. 5 is a top plan view thereof; and,

FIG. 6 is a bottom plan view thereof.

The surface indicia shown in broken lines forms no part of the claimed design.
